CLAIM

The ornamental design for a hoop earring, as shown and described.

DESCRIPTION

FIG. 1 is a front perspective view of hoop earring showing my new design;

FIG. 2 is a top view thereof;

FIG. 3 is a bottom view thereof;

FIG. 4 is a front view thereof;

FIG. 5 is a rear view thereof;

FIG. 6 is a left view thereof; and,

FIG. 7 is a right view thereof.

The broken lines depicting an earring post and unclaimed portions of the hoop earring form no part of the claimed design.
